UNITED STATES PATENT OFFICE.

CHARLES VOLNEY KERR, OF WELLSVILLE, NEW YORK.

BLOWER.

1,136,142.

Specification of Letters Patent. Patented Apr. 20, 1915.

Application filed August 15, 1913. Serial No. 765,009.

To all whom it may concern:

Be it known that I, CHARLES V. KERR, a citizen of the United States, residing at Wellsville, New York, have invented a certain new and useful Blower, of which the following is a specification.

One object of my invention is to increase the efficiency of blowers employed for forced draft, or other purposes, by providing improved diffusion means which prevent losses by eddy currents, etc. More particularly, I accomplish this result by employing, at the discharge side of the fan, an annular discharge nozzle, and in this nozzle I provide a number of stationary blades or vanes. These blades are preferably curved so that they receive air from the fan traveling in its normal direction and discharge this air radially. In effect, these blades divide the annular discharge or diffusion nozzle into a plurality of nozzles, in place of the usual volute casing, each of which is larger at the discharge end than at the inner end. Air passing into the small ends of the nozzles is thus reduced in velocity with increase of pressure so that the kinetic energy imparted by the fan is most efficiently converted into potential energy. Air is discharged from the circular, vaned diffuser into an inclosed space such as the stokehole of a vessel for example, and the combination specified is especially adapted to maintain suitable pressure in such an inclosure in an efficient manner and without the provision of a volute casing which is frequently employed in compressors.

Another principal object of the invention is to reduce the noise of blower-fans and the like by making the number of blades in the fan and the number of blades in the diffuser prime to each other. This prevents the whole number of blades in the rotor and stator from passing through the same phase with respect to each other at the same instant, and regular vibrations which would cause unreasonable noise are thus prevented.

The accompanying drawing shows the invention in a form particularly designed for producing forced draft in vessels where the air is discharged directly into the stokehole or fire room; but, evidently, details of construction and range of application of the invention may vary greatly.

Figure 1 is a downward view partly in

plan and partly in section of half of the apparatus, and Fig. 2 is a vertical section.

Reference character 1 designates a suction passage leading through the deck 2 of a vessel, or the like. This suction passage terminates in what may be identified as a suction-throat 3. The impeller shaft 4 supports impeller 5 within the throat. At the discharge side of the impeller is deflector 6, preferably of conoidal shape. The inner end of suction-throat 3 is curved and flanged outward, and an annular diffuser surrounding the deflector is formed by plates 7 and 8 secured to the suction-throat and outer edge of the deflector, respectively. Within this diffusion ring or nozzle are a plurality of vertical diffusion blades or vanes 9, and these are preferably curved, as shown in Fig. 1. The diffusion ring thus constitutes essentially a multiple volute discharge casing. Air is discharged by the fan through the space between the suction-throat and the deflector, and strikes the inner ends of the diffusion vanes in nearly tangential lines, as indicated by the arrows, Fig. 1, and the vanes direct this air outward in radial lines, as shown. The cross-sectional area of each subordinate nozzle increases from the inlet to the outlet sides, and thus each component part of the diffusion ring forms part of a volute casing.

To reduce noise in the way above suggested, the number of blades in the fan may, for example, be thirty-one, and the number of blades in the diffuser may be thirty-two. These numbers are prime to each other, and, therefore, produce the desired result in reducing noise. Other numbers of blades prime to each other may be chosen, but it will probably usually be desirable to make the number of blades closely approach each other, although this is not an essential limitation.

M designates a suitable motor, such as a steam turbine mounted on the impeller shaft and suitably suspended. Any suitable high-speed motor designed to coöperate with the impeller may, of course, be employed.

The invention is designed for advantageous use of an impeller of the kind described in my previous pending applications, Serial Numbers 648,584 and 665,785, although it is not limited to the use of that form of impeller.

I claim:

1. In a blower or the like, a bladed impeller and a diffuser having stationary blades, the number of blades in the impeller and diffuser being prime to each other.
2. In a blower or the like, the combination of a rotary bladed impeller designed to move air axially, a deflector at the discharge side of the impeller, an annular diffusion ring at the periphery of the deflector, said ring being in a plane parallel to the rotative plane of the impeller, and diffusion vanes in the diffuser, the number of the impeller blades being prime to the number of the diffusion vanes to reduce the noise of operation.
3. In a blower, the combination of a rotary bladed impeller, a circular casing therefor having a suction inlet to supply air to the impeller, and a concentric series of diffusion vanes to receive air from the impeller, the number of the impeller blades being prime to the number of the diffusion vanes to reduce noise.
4. In a blower or the like, the combination of a suction inlet, an impeller for moving air axially rotatably supported within said inlet, a stationary deflector at the discharge side of the impeller arranged to receive air moving axially and to deliver it spirally outward, an annular series of diffusion vanes to receive air from the deflector and deliver it radially outward, and an inclosure for containing air under pressure wherein said diffusion vanes are located.

tion of a suction inlet, an impeller for moving air axially rotatably supported within said inlet, a stationary deflector at the discharge side of the impeller arranged to receive air moving axially and to deliver it spirally outward, an annular series of diffusion vanes to receive air from the deflector and deliver it radially outward, and an inclosure for containing air under pressure wherein said diffusion vanes are located. 30

5. In a blower or the like, the combination of a suction inlet, an impeller rotatably mounted therein and constructed and arranged to move air spirally away from said inlet, an annular series of diffusion vanes 40 arranged concentric with said impeller to receive air therefrom and deliver it radially outward, and an inclosed space wherein said series of diffusion vanes is mounted for containing air under pressure.
